US0D1113864S

(12) **United States Design Patent** (10) Patent No.: **US D1,113,864 S**
(45) Date of Patent: ** Feb. 17, 2026

(54) **EARPHONE**

(71) Applicant: **SHENZHEN SHOKZ CO., LTD.**,
Guangdong (CN)

(72) Inventors: **Lei Zhong**, Shenzhen (CN); **Zeteng Yan**, Shenzhen (CN); **Sunjie Huang**, Shenzhen (CN); **Haochen Liu**, Shenzhen (CN); **Haofeng Zhang**, Shenzhen (CN); **Jiang Xu**, Shenzhen (CN); **Zeying Zheng**, Shenzhen (CN)

(73) Assignee: **SHENZHEN SHOKZ CO., LTD.**,
Shenzhen (CN)

(**) Term: **15 Years**

(21) Appl. No.: **29/995,512**

(22) Filed: **Mar. 26, 2025**

Related U.S. Application Data

(62) Division of application No. 35/520,303, filed on Mar. 15, 2023 (U.S. filing date under 35 U.S.C. 384), and having an international filing date of Mar. 15, 2023.

CLAIM

The ornamental design for an earphone as shown and described.

DESCRIPTION

FIG. 1 is a perspective view of an earphone showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
